UNITED STATES PATENT OFFICE.

WILLIAM E. PALMETER, OF ELMWOOD, NEBRASKA.

CONCRETE-MIXER.

1,388,118.

Specification of Letters Patent. Patented Aug. 16, 1921.

Application filed January 2, 1920. Serial No. 348,755.

To all whom it may concern:

Be it known that I, WILLIAM E. PALMETER, a citizen of the United States, and resident of Elmwood, in the county of Cass 5 and State of Nebraska, have invented certain new and useful Improvements in Concrete-Mixers, of which the following is a specification.

The present invention relates to concrete 10 mixers and has for its primary object the provision of a concrete mixer of the rotatable type having means for driving the mixer while performing a mixing operation and while being emptied.

15 Another object of my invention is to provide a concrete mixer of the class described having an even driving means imparting a continuous action to the mixer regardless of the position of the same.

20 A further object of my invention is to provide a concrete mixer of the class described which is strong and durable, effective in operation, cheap to manufacture and simple in construction.

25 Other objects and advantages to be derived from the use of my improved concrete mixer will appear from the following detail description and the claim, taken with an inspection of the accompanying drawings in which:

Figure 1 is a side elevational view of a concrete mixer embodying the improvements of my invention;

Fig. 2 is a similar view of the opposite 35 side of the machine, the same being shown tilted for filling;

Fig. 3 is a top plan view of the same, a portion of the mixer being broken away; and

40 Fig. 4 is a transverse sectional view of the mixer.

Referring more particularly to the drawings, wherein similar characters of reference designate like and corresponding parts throughout the various views, 10 designates the longitudinal parallel stringers of the base frame of my improved mixing device, said stringers 10 being connected by transverse stringers 11.

45 Standards 12, 13 and 14 are mounted on the stringers 10, the upper free ends of said standards being formed with bearings 15, 16 and 17, respectively.

The mixer carrying frame is designated

F in its entirety and is preferably U-shaped, 55 said frame being provided with a transverse portion 18 and parallel arms 19, said arms being provided with trunnions 20 and 21, the trunnion portion 21 being hollow for a purpose which will hereinafter appear. 60 The trunnions 20 and 21 are mounted in the bearings 15 and 16. A lever 22 is mounted on the free end of the trunnion 20 for oscillating the same for a purpose which will hereinafter appear. The mixer container 65 includes a cylindrical hollow member 23 having a bearing trunnion 24 on the rear end thereof, said bearing trunnion engaging the transverse portion 18 of the frame F. A bearing ring 25 is carried by the free ends 70 of the arms 19, said bearing rings encircling the container 23 adjacent the front end thereof, a plurality of bearing rollers 26 being carried by said rings and engaging said container. The container 23 is provided interiorly with the usual spiral agitating blade 27.

The driving mechanism for the container 23 includes a pulley wheel 28 carried on a shaft 29, said shaft being journaled in the 80 trunnion 21 and bearing 17. A driving wheel 30 is mounted on the inner end of the shaft 29, said wheel having pins 31 thereon for engagement with an angle-iron 32 carried on the container 23, said angle-iron being provided with a plurality of apertures 85 33 spaced for engagement by said pins 31.

In using my improved mixer power is imparted to the mixing container 23 from the pulleys, and when it is desired to tilt the 90 container for emptying while in motion, the lever 22 is raised. When the mixer is in operation, the container 23 is disposed with its open end elevated, the extremity of the lever 22 bearing upon the ground, as indicated in Fig. 2, thus maintaining the container in a rearwardly inclined position, and acting to brace and steady the same and its supporting frame during the mixing operation. Thus it will be seen that in the provision of my improved mixer I afford means for thoroughly mixing concrete and the like without the provision of complicated and inefficient supporting and driving means. I 100 desire to lay particular stress upon the light 105 and durable construction of the device permitting rotation of the container during the tilting. If desired the device may be mount-

ed on a truck or the like, however, the showing made in the drawing is the preferred arrangement of my invention.

From the above description taken in connection with the accompanying drawings, it is thought that a clear and comprehensive understanding of the construction, operation and advantages of my invention may be had, and while I have shown and described the device as embodying a specific structure, I desire that it be understood that such changes may be made in said structure as do not depart from the spirit and scope of the invention as claimed.

Having thus fully described my invention, what I claim as new and desire to secure by Letters Patent, is:

In a concrete mixer, a cylindrical mixer

container normally disposed in upwardly inclined position and having its upper end open, a support for said container, means for rotating said container, and a lever connected to said container and extending outwardly and downwardly at one side of the same beyond the closed end thereof and at an angle to the axis of the container, the free end of said lever normally acting to sustain said container in position for the mixing operation and also acting to brace the same and said support during such operation, said lever being operable for tilting said container to and from dumping position.

In testimony whereof I affix my signature hereto.

WILLIAM E. PALMETER.
